UNITED STATES PATENT OFFICE

2,202,818

WINDOW

Alvin M. Whitney, Bradford, Pa.

Application December 30, 1938, Serial No. 248,616

1 Claim. (Cl. 20—52)

The present invention relates to new and useful improvements in windows of the type comprising vertically sliding sashes and has for its primary object to provide, in a manner as hereinafter set forth, novel means for assisting in raising the sashes.

Another very important object of the invention is to provide a window structure of the character described comprising novel means for weatherstripping the sashes.

Still another important object of the invention is to provide a window of the aforementioned character embodying a construction and arrangement which is such that the sashes may be expediently removed from the frame when necessary for any reason, as when access is desired to the lifting and weatherstripping means.

A still further important object of the invention is to provide a window structure comprising unique means for firmly securing the sashes against sliding movement in any position.

Other objects of the invention are to provide a window which will be comparatively simple in construction, strong, durable, highly efficient and reliable in operation, attractive in appearance, and which may be manufactured and installed at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view partially in front elevation and partially in vertical section, showing a window constructed in accordance with the present invention.

Figure 2 is a view in horizontal section, taken substantially on the line 2—2 of Fig. 1.

Figure 3 is a vertical sectional view through the frame with the sashes omitted.

Figure 4 is a perspective view of a side portion of the lower sash.

Figure 5 is a vertical sectional view, taken substantially on the line 5—5 of Fig. 3.

Figure 6 is a vertical sectional view, taken substantially on the line 6—6 of Fig. 5.

Figure 7 is a detail view in perspective of one of the sash locks.

Figure 8 is a perspective view of an end portion of one of the combination sash lifting straps and weatherstrips.

Referring now to the drawings in detail, it will be seen that the embodiment of the invention

which has been illustrated comprises a frame which is designated generally by the reference numeral 1. As best seen in Fig. 2 of the drawings, the frame 1 is constructed in a manner to provide vertical side chambers 2. Mounted for vertical sliding movement in the frame 1 are upper and lower sashes 3 and 4, respectively.

As also shown to advantage in Fig. 2 of the drawings, the frame 1 includes vertical side members 5 and 6 having projecting therefrom guides 7 between which the sashes 3 and 4 are slidable. The members 5 are permanently secured in the frame structure 1 while the outer members 6 are removable to permit removal of the sashes 3 and 4. The adjacent vertical marginal portions of the members 5 and 6 are rabbeted in a manner to define, in conjunction with each other, grooves 8 the purpose of which will be presently set forth. The vertical side edges of the sashes 3 and 4 are also provided with grooves 9 which are opposed to the grooves 8 and the purpose of which will also be presently set forth.

Mounted on the members 5 and 6 in the chambers 2 of the frame 1 are metallic casings 10. Rotatably mounted in the casings 10 are peripherally grooved pulleys 11. Springs 12 in the pulleys 11 are connected to said pulleys in a manner to be wound thereby when said pulleys are rotated in one direction. The casings 10 extend through openings which are provided therefor in the members 5 and 6 of the frame 1 and are secured thereto by vertical flanges 13. The flanges 13 extend vertically from the inner walls 14 of the casings 10 and it will be observed that said flanges are recessed in the inner sides of the members 5 and 6. This is shown to advantage in Fig. 5 of the drawings. The flanges 13 and the inner walls 14 are provided with vertical grooves constituting continuations of the grooves 8.

It will be observed that two casings 10, pulleys 11, etc., are provided for each sash 3 and 4, one on each sash in the frame structure 1. The inner walls 14 of the casings 10 have formed therein openings 15 for the passage of flexible straps 16 of suitable material which travel around the pulleys 11. The end portions of the straps 16 are firmly secured to the upper and lower portions of the sashes 3 and 4, as at 17. Grooved rollers 18 are journalled between the side walls of the casings 10 in the openings 15 over which the straps 16 travel as they enter and leave said casings. Projecting from the opposite sides of the flexible straps 16 are longitudinally extending beads or ribs 19 which travel in the grooves 8 and 9.

9 in a manner to close and seal the space between the vertical sides of the sashes 3 and 4 and the opposed side portions of the frame 1. The beads or ribs 19 are of suitable resilient material, preferably rubber.

5 Mounted in the openings 16 in the casings 10 between the rolls 18 are locks 20 for the sashes 3 and 4. The locks 20 are in the form of shoes which are frictionally engageable with the vertical sides of the sashes 3 and 4. Also, the locks 20 are shaped to substantially close the space between the ingoing and outgoing portions of the straps 16 in the openings 15 of the casings 10. Referring now to Figs. 5, 6 and 7 of the drawings, it will be seen that the locks 20 have formed therein openings 21 which accommodate cam shafts 22 which extend between the side walls of the casings 10. It may be well to here state that the cam shafts 22 constitute means for engaging the locks 20 with the sashes 3 and 4. The cam shafts 22 project beyond one side of the casings 10 through the frame structure 1 and have formed therein square sockets 23 (see Fig. 6) which are adapted to receive an operating key 24.

10 25 It is thought that the operation of the invention will be readily apparent from a consideration of the foregoing. When the sashes are lowered the straps 16 travel around the pulleys 11 and frictionally drive said pulleys in a direction 20 to wind the springs 12. Thus, when it is desired 30 to raise the sashes the operation is materially assisted by the springs 12. The flexible lifting straps 16, with the ribs or beads 19 thereon traveling in the grooves 8 and 9, constitute weather- 35 strips for the sashes 3 and 4. By actuating the

cam shafts 22 the locking shoes 20 are engaged with the vertical sides of the sashes 3 and 4 for frictionally clamping said sashes against vertical movement in any desired position in the frame 1. The faces of the locking shoes 20 are 5 provided with vertical ribs 25 which are engaged in the grooves 9 of the sashes 3 and 4. Of course, by rotating the cam shafts 22 in the opposite direction the locking shoes 20 are retracted for releasing the sashes 3 and 4. When it is 10 desired to remove the sashes 3 and 4 for any reason this may be expeditiously accomplished by simply removing the outer vertical side members 6 of the frame structure 1.

15 It is believed that the many advantages of a window constructed in accordance with the present invention will be readily understood and although a preferred embodiment of said window is as illustrated and described, it is to be understood that changes in the details of construction 20 and in the combination and arrangement of parts may be resorted to which will fall within the scope of the invention as claimed.

What is claimed is:

A window comprising a frame, a sash slideable 25 in said frame, said sash and said frame having opposed grooves therein, a flexible strap connected to the sash and operable between said sash and frame, means for actuating the strap for urging the sash in one direction, and beads 30 on the strap engageable in the grooves and, in conjunction with said strap, constituting means for closing the space between the sash and the frame.

ALVIN M. WHITNEY. 35
